Steven J. Kim; KLEINBERG & LERNER, LLP

(57) **CLAIM**

The ornamental design for a shoe insole, as shown and described.

DESCRIPTION

FIG. 1 is a front top perspective view of a shoe insole in accordance with my new design;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed lines represent environmental portions of the shoe insole that form no part of the claimed design.

1 Claim, 6 Drawing Sheets
